JOHN L. PREO AND ISABELLE HENNE, OF NEW YORK, N. Y.

WOODEN FRENCH SHOE-HEEL.

1,340,910.

Specification of Letters Patent. Patented May 25, 1920.

Application filed September 18, 1919. Serial No. 324,436.

To all whom it may concern:

Be it known that we, JOHN L. PREO and ISABELLE HENNE, citizens of the United States, residing in the city and State of New York, have jointly invented a new and useful Improvement in Wooden French Shoe-Heels, of which the following is a specification.

The invention relates to wooden French shoe heels, and the object is to provide a combined fastening for securing the heel to the shoe and the top-lift to the heel, without the danger of breaking and chipping the edges of the heel by the nails usually employed for attaching the lift, and in such manner that the top-lift can be removed when worn and replaced by another without disturbing the fastening of the heel. This is accomplished by means of a three-piece fastening extending longitudinally or axially through a preformed opening in the heel, the same comprising an upper member having a screw-threaded stem inserted downward into the upper part of the opening and having a head to overlie a portion of the sole, an intermediate headed or shouldered member inserted upward from the bottom and screw-threaded to engage the upper member and thereby clamp the heel to the shoe, and a bottom headed screw which is passed upward through an interior hole in the top-lift into the axial hole of the heel, where it engages a tapped socket in the intermediate member.

In the accompanying drawings, forming a part hereof:

Figure 1 is a partial side elevation of a shoe, with the heel in section:

Fig. 2 is a view, looking upward, taken on the line 2—2 of Fig. 1; and

Fig. 3 is a perspective view showing the fastening member.

The drawing illustrates a wooden French heel body of usual form, 2 is the leather top-lift, and 3 is the portion of the sole to which the heel is secured.

The heel is formed with a bored hole extending substantially centrally from top to bottom, said hole comprising an intermediate portion of relatively narrow diameter and upper and lower portions of relatively wide diameter. A fastening member 4 has a stem 5 inserted downward through a slot in the insole into the upper part of

the hole, fitting the same, and a flat, rearwardly disposed head 6 bearing upon the upper side of said insole. The stem 5 is hollow and is internally screw-threaded from the bottom upward. This member is advantageously constructed of a single piece of sheet metal having its lower portion rolled to form the tubular stem and its upper portion bent back flat in obtuse angular relation to form the head.

A long externally-threaded screw 7 having a kerfed head 8 at its lower end extends upward through the intermediate, narrower portion of the hole in the heel and screws into the stem of the upper member. When the screw is screwed up tight its head bears against the shoulder in the lower part of the heel and the head is drawn down upon the top of the sole or insole, the relation being such that the heel is firmly clamped in place, and by a pressure which bears particularly at the back, so that gaping is overcome.

The lower headed part of the screw 7 is also recessed and internally threaded, and this socket 9 is engaged by the third member consisting of a short headed screw 10. This screw passes through an opening in the interior region of the top-lift 2, into said socket 9, and when tightened firmly holds the top-lift without possibility of injuring the delicate edges of the wooden body. When the top-lift is to be taken off and a new one put on, the screw 10 is removed, but this does not affect the body of the heel which remains rigidly clamped in place.

What we claim as new is:

1. The combination with a high wooden shoe heel having an opening extending from its top to its bottom, and a top-lift, of a member having a threaded stem inserted downward from the top of the opening and a head to overlie a portion of the sole of the shoe, a second threaded member inserted upward in the opening from below to engage the first threaded member and thereby fasten the heel to the shoe, and a screw passing through the top-lift and threaded into said second member to secure the top-lift.

2. The combination with a high wooden shoe heel having a shouldered opening extending from its top to its bottom, and a

top-lift, of a member having an internally-threaded stem in the upper part of the opening and a head to overlie a portion of the sole, a long headed screw extending upward in the opening and engaging said internally-threaded stem, whereby the heel is clamped in place, said screw having a

threaded socket in its lower portion, and a short screw fastening the top-lift extending upward into the socket of the long 10 screw.

**JOHN L. PREO,
ISABELLE HENNE.**
